UNITED STATES PATENT OFFICE.

JOSEPH WODELL, OF NEW YORK, N. Y., ASSIGNOR TO THE BOYNTON FURNACE COMPANY, OF SAME PLACE.

FURNACE AND GRATE.

SPECIFICATION forming part of Letters Patent No. 439,229, dated October 28, 1890.

Application filed March 3, 1890. Serial No. 342,470. (No model.)

To all whom it may concern:

Be it known that I, JOSEPH WODELL, a citizen of the United States, residing in the city of New York, in the county of New York, in 5 the State of New York, have invented a new and useful Improvement in Furnaces and Grates, of which the following is a description.

The object of the invention is to provide means for preventing the misadjustment of 10 grates or grate-bars; and the invention consists in certain novel parts and in certain novel combinations of parts in or in connection with a grate or a grate-bar and in or in connection with a furnace or other heater in 15 which such grate or grate-bar is employed, whereby it is rendered impossible, either through inadvertence or otherwise, to leave the same in a condition of improper adjustment.

20 In the drawings, Figure 1 represents a view in perspective of a portion of one form of grate to which my improvement is applicable, the covering-shield of the interlocking mechanism having been removed. Fig. 2 is a view 25 of the adjusting-plate or journal-plate detached. Fig. 3 is a plan view of the operating-lever, showing the receiving-face of the same. Fig. 4 is a perspective view of the operating-lever. Fig. 5 represents a modification. Fig. 6 is a transverse section of one of 30 the triangular grate-bars, which in this example illustrate the invention.

In this instance the grate, as A, is composed 35 of a series of bars a, each bar being in its main portion of a generally triangular form in transverse section—that is, having three concentric equidistant fuel-supporting surfaces, as is common—and the whole being connected for operation in an ordinary manner 40 by suitable gear-wheels a', which are fixed concentrically upon the shank of the bar. One of the members of the series of bars is provided with an extended shank or spindle a'', the outer extremity a''' of which is transversely 45 of substantially triangular form, as seen in Fig. 1, the planes of the triangle corresponding with the planes of the body of the bar. The end a''' of the shank projects outwardly through an opening o in the adjusting or 50 guide plate B, and is concentric with the in-

ner face of the guide-lugs b', b'', and b''', which project outwardly from the vertical exterior face of the same, and which are each provided with a recess or inhang, as seen in Fig. 1 and as indicated in dotted lines in Figs. 2 and 5. 55

As will be apparent to persons conversant with the art, the opening for the grate or section shank and the guide-lugs—one or more—employed in connection therewith may be provided in the grate-front itself; but in practice 60 it has been found advantageous to provide these in a separate plate, which in being applied may be more readily adjusted to the position of the projecting shank of the bar or section. 65

As will be seen in Fig. 2 of the drawings, the lugs b', b'', b''' are triangularly arranged, and in practice they are at such distances apart that the inclosed space is just sufficient when the grate bar or section is in its proper fuel-supporting adjustment to permit the insertion and manipulation of the operating or 70 grate-shaking lever, but is insufficient to permit the withdrawal of such lever when such bar or section is in any other adjustment. 75

Under the construction seen in Fig. 5 in the drawings instead of the three lugs b', b'', b''' a single lug b is employed, its configuration and its relation to the shank a'' of the bar or section being such that the operating-lever is 80 not withdrawable therefrom except when such bar or section has been brought into its proper fuel-supporting position.

As shown in Figs. 3 and 4, the operating-lever C has an engaging-orifice c', by which 85 it is rendered readily applicable to the triangular end a''' of the shank a''; but it will be apparent that the parts might be adapted to each other in various other ways.

It will be understood that the invention is 90 applicable with equal advantage to a single bar or to any one-part laterally-tilting grate or grate-section which is provided with a triangular or other analogous operating-shank.

The invention having been thus described, 95 what is claimed is—

In a furnace or heater, a front plate which is provided upon its outer surface with recessed or indrawn outwardly-extending lugs, one or more, and which has a perforation ad- 100

ja cent to such lug or lugs, a grate bar or section which has a shank which extends outwardly through the perforation in the furnace-front, and an operating-lever which is adapted to engage the shank of the bar or section and to be reciprocated, and which is in such relation to the lug or lugs that it is not withdrawable from its engagement with the

shank except when such bar or section is in its proper fuel-supporting position, in combination, substantially as set forth.

JOSEPH WODELL.
